UNITED STATES PATENT OFFICE.

JAMES OLIVER, OF SOUTH BEND, INDIANA, ASSIGNOR TO THE SOUTH BEND IRON WORKS, OF SAME PLACE.

PLOW.

SPECIFICATION forming part of Letters Patent No. 628,632, dated July 11, 1899.

Application filed May 16, 1899. Serial No. 717,076. (No model.)

To all whom it may concern:

Be it known that I, JAMES OLIVER, of South Bend, in the county of St. Joseph and State of Indiana, have invented certain new and useful Improvements in Plows; and I do hereby declare the following to be a full, clear, and exact description of the invention, such as will enable others skilled in the art to which it appertains to make and use the same.

My invention relates to an improvement in plows, the object of the same being to so construct a plow standard and moldboard that when the latter is placed on the standard it seats itself solidly against the adjacent edge of the plow-point, thus obviating the necessity of forcing the moldboard to its seat by the screw-bolts which secure it to the standard.

A further object is to provide a standard constructed to receive either an ordinary chilled moldboard or steel mold which are of different thicknesses and support them both with their outer faces flush and on line with the contour of the point.

A further object is to strengthen the moldboard at or near the point where the rear edge of the plow-standard joins the moldboard or at the point where the greatest strain falls on the moldboard.

With these ends in view my invention consists in the parts and combinations of parts, as will be more fully described, and pointed out in the claims.

In the accompanying drawings, Figure 1 is a view of my improved plow. Fig. 2 is a view of the standard and moldboard, the latter being detached. Fig. 3 is a sectional view through the plow, and Fig. 4 is a view showing the steel moldboard on the standard.

A represents a standard of usual shape carrying the landside B and point C, the landside and point being secured to the standard in the usual manner. The standard is provided on its front face, near the upper edge of the point, with a tapered or inclined lug a, adapted to enter a depression b, formed in the under side of the chilled or cast moldboard, the lug and depression being so formed that when the moldboard is bolted to the standard the lug a forces the moldboard downwardly and forwardly against the upper or rear edge of the plow-point, thus making a close-fitting joint

and rendering it impossible for the moldboard to work away from the plow-point.

In plows as heretofore constructed the bolt-holes in the moldboard and standard were so constructed and located with relation to each other that the act of driving the bolts home forced the moldboard against the point and the bolts alone held the moldboard in place. With such construction the driving of the bolts home marred their threads to such an extent that the bolts were unfit for use after being once taken apart. With my improved construction the tapered lug on the standard and corresponding depression on the under side of the moldboard tend naturally to hold the moldboard against the upper edge of the point, and hence when the bolts are secured in place all the tendency to movement of the moldboard is borne by the lug. Hence the bolts simply operate to hold the moldboard seated against the standard and do not receive any of the rearward thrust or strain falling on the moldboard. The standard A is also provided at intervals through its front face with a series of lugs c, having flat upper faces. These lugs c are of a height equal to the difference in thickness between the ordinary chilled moldboard and the steel moldboard.

The chilled or cast moldboard A is provided with depressions d in its rear face to receive the lugs c on the standard A, thus permitting the moldboard to rest solidly on the standard with its outer face flush with the outer face of the point and conforming to the contour of the point, whereas the steel moldboard D' rests on the lugs and is supported with its outer face flush with the outer face of the point. The steel moldboard D' is provided on the rear side of its front edge with a rib d', which latter is adapted to rest against the standard and form a close joint therewith. With this construction it will be seen that the moldboards are interchangeable, thus adapting the standard for either the thick cast moldboard or the comparatively thin steel moldboard.

The strain on the moldboard falls on the point or line where the rear end of the moldboard overlaps or overhangs the rear edge of the standard, and one object of my invention is to prevent to a large extent the breakage

of moldboards at this point. This object I accomplish by providing the standard A near its top with a groove or depression e, gradually decreasing in depth rearwardly and providing the rear face of the cast moldboard D with an upwardly and rearwardly extending rib f, cast integral with the moldboard. This rib extends rearwardly, after leaving the standard, along the upper edge of the moldboard and is thickest at the point where the moldboard leaves the standard, and hence operates to a large extent to prevent breakage of the moldboard at this point.

It is evident that many slight changes might be made in the relative arrangement of parts herein shown and described without departing from the spirit and scope of my invention. Hence I would have it understood that I do not wish to restrict myself to the exact construction of parts herein shown and described; but,

Having fully described my invention, what I claim as new, and desire to secure by Letters Patent, is—

- 25 1. In a plow, the combination with a standard having a tapered lug on its outer front face, of a moldboard having a depression adapted to receive said lug, and bolts for locking the moldboard in place.
- 30 2. In a plow, the combination with a standard having a tapered lug on its outer front

face, and a point secured to the standard below or in advance of the lug, of a moldboard having a shoulder located in a depression on its rear face the said shoulder adapted to engage the tapered lug for holding the moldboard solidly against the rear edge of the point and bolts for locking the moldboard in place.

3. In a plow, the combination with a standard having a series of lugs disposed at intervals on its outer front face, said lugs adapted to form seats or supports for a thin steel moldboard, or rest within depressions formed in a thicker cast moldboard, of a plow-point secured to the standard, substantially as set forth.

4. In a plow, the combination with a standard having a groove formed in its front face near its upper edge, of a moldboard having an integral rib adapted to rest within said groove, the rib projecting rearwardly or laterally beyond the rear edge of the standard, substantially as set forth.

In testimony whereof I have signed this specification in the presence of two subscribing witnesses.

JAMES OLIVER.
